METHOD AND APPARATUS FOR DILUTING
ROSIN SIZEEdgar A. Howell, New York, N. Y., assignor to
American Cyanamid Company, New York, N. Y.,
a corporation of Maine

Application January 31, 1951, Serial No. 208,677

3 Claims. (Cl. 137—165)

1

This invention relates to a method and apparatus for diluting rosin sizes from concentrated dispersions to the dilute aqueous condition in which they are used in paper mills. The invention includes a two-stage dilution and homogenization of the rosin size as well as the novel apparatus or system provided therefor, including certain safety features, that will hereinafter be more fully described.

Rosin sizes are usually produced by saponifying wood rosin, gum rosin, tall oil rosin or other types of abietic acid with alkalies. In preparing liquid rosin sizes the rosin is ordinarily heated with an aqueous solution of sodium or potassium carbonate, usually employing about 9—16% of the carbonate, based on the weight of the rosin, at about 190—212° F. for about 6 hours. In the preparation of dry rosin size the rosin may be reacted with about 9—12% of sodium or potassium hydroxide in the form of a relatively concentrated aqueous solution, which produces the dry rosin size directly, or a liquid size may be evaporated on a drum drier or by spray drying.

Liquid rosin sizes are usually sold to paper mills at concentrations of about 70—80% solids, the liquid portion being either all water or, in some cases, with the addition of a small proportion of ethanol, ethylene glycol or other alcohol. The dilution of these concentrated sizes has heretofore presented a definite problem, for the size goes through a gel stage upon dilution with cold water and is more viscous at intermediate concentrations of, for example, 30—40% solids than it is at 70—80% solids. It is necessary, therefore, to heat the concentrated rosin size solution and to dilute it initially with hot water until a concentration below the gel stage is obtained; with most sizes a safe limit of dilution with hot water is about 10—20% solids. Further dilution may then be made with cold water until the concentration is reached at which the size is to be mixed with the paper pulp, this concentration usually being about 1—5% solids.

The present invention has as a principal object the provision of a method whereby concentrated liquid rosin sizes are heated and diluted continuously and automatically with hot water to the desired gel-free intermediate concentration and are finally homogenized to produce a uniform dispersion after which they are further diluted with cold water and again homogenized to form the finished dilute rosin size having a concentration suitable for use in a paper mill. A further object of the invention resides in the provision of an apparatus for carrying out this

2

heating, dilution and homogenization. A still further important feature of the invention resides in the provision of safety interlocks between the various elements and sub-combinations of apparatus whereby damage to the system or to the size is avoided in case of failure of any of the component parts. The importance of the above and other objects of the invention will become apparent from the following description of a preferred embodiment thereof, when taken with the appended claims.

The invention will be further described with reference to the accompanying drawings, where-in Fig. 1 is a diagrammatic illustration of a dilution system in accordance with the invention, Fig. 2 is a vertical section of a Venturi mixer for diluting the liquid rosin size with hot water, and Fig. 3 is a similar section of a constant back-pressure valve employed in practicing the process.

Referring to Fig. 1 of the drawings, a concentrated liquid rosin size which may be, for example, of 70% solids, is fed into a constant delivery pump 1 from a storage tank that is not shown. This pump may be, for example, a gear pump of from $\frac{3}{4}$ gallon to 3 gallons per minute capacity. The rate of discharge of size from the pump is adjusted by a manually operated speed control 2 which is adjusted in accordance with the quantity of dilute rosin size required by the paper mill. The pump operates against a constant back-pressure valve 3, constructed as shown in Fig. 2 and to be described later, from which the size is passed through pipe 4 into a heater 5. In this heater, which may advantageously be of the spiral plate type, the size is heated to a temperature within the dilution range, which may lie within the temperature range of from about 140° F. to about 200° F. or higher. It will be understood that different types of sizes may have different temperature-viscosity curves during dilution; however, in practically all cases gel formation can be offset by diluting at temperatures above about 140° F. In the particular system illustrated, 170° F. has been selected as the dilution temperature as this temperature provides a considerable margin of safety and is easily attained in the system described.

The system for maintaining a constant supply of hot water having a definite temperature, and of delivering this hot water at a constant but adjustable rate, constitutes an important feature of the invention. A hot water tank 10, which is provided with a float-controlled inlet

valve 11 for cold water, may advantageously be of 50 gallons capacity. Water from this tank is withdrawn constantly through a lower line 12 by a pump 13 and passed through a steam injector 14 after which it may recirculate back to the tank 10 through line 15 provided with a manually adjustable constant back-pressure valve 16. The steam is supplied through line 17 and valve 18, which is a thermostatically controlled valve that operates in response to the temperature of the water in line 16 as indicated by the dotted line 19. By introducing the steam into a recirculating side line in this manner, the development of steam hammering is eliminated.

Constant delivery of hot water from the storage tank 10 is obtained by operation of the pump 13 against the constant back pressure of the valve 16 which may be set (for example) at 70 pounds pressure. The setting of this valve determines the maximum back pressure of the pump system, since a higher back pressure will cause the valve to open. The hot water is withdrawn from the system by way of pipe 20 through a high lift V-port manually adjusted valve 21, whereby the rate of flow is adjusted to the amount indicated on a flow meter 22. The capacity of the pump 13 is substantially larger than the maximum flow of water to be withdrawn through valve 21, so that some water is always recirculated through valve 16 and line 15 maintaining a constant back pressure, and therefore a constant flow of hot water is always obtained through the valve 21 and meter 22.

Uniform mixing of a constant flow of rosin size from the heater 5 with a constant flow of hot water from the tank 10 is obtained by means of a Venturi mixer 25, the structure of which is shown in Fig. 2 of the drawings. Reference to this figure will show that the hot water, introduced through inlet 26, is directed through nozzle 27 into the throat of a Venturi tube 28. Meanwhile the hot rosin size solution is admitted through inlet 29 and passes uniformly into the flared end 30 of the venturi. Uniform mixing is obtained by the turbulence created within the restricted portion of the tube 28, and the resulting diluted size dispersion is discharged through outlet 31 into pipe 32. Experience has shown that a highly uniform dispersion of diluted rosin size is obtained by this procedure.

The diluted rosin size dispersion obtained from the Venturi mixer 25 is homogenized to free it from lumps or other manifestations of gel formation by passage through a constant back-pressure valve 34 having the structure shown in Fig. 3 of the drawings. Referring to this figure it will be seen that constant back pressure is obtained by the force of a disc 35 working against the upper edge 36 of an outlet pipe 37. The rosin size dispersion is admitted through inlet 38 and passes upwardly through pipe 39 into an annular chamber 40 that surrounds the disc 35. Constant back pressure is obtained by the force of a spring-pressed plunger 41, which presses by means of diaphragm washer 42 and diaphragm 43 upon the disc 35. Passage of the rosin size between the annular edge 36 and the bottom surface 44 of the disc 35 results in homogenization with the production of a completely uniform size dispersion that is discharged through the outlet 45 into line 46. In the preferred practice of the invention the rosin size is discharged from valve 34 as a 12% solution.

The concentration of the size solution in the pipe 46 is well below that of gel formation, and therefore the size can safely be diluted with cold

water; i. e., with water from the ordinary supply of a paper mill such as that having temperatures of 35°-70° F. In order to control the final concentration, however, it is again necessary to provide a flow of water having a constant predetermined rate, and this is done by an additional feature of the present invention. The cold water supply is admitted through a booster pump 51 which works against a pressure reducing valve 52. This valve is so constructed as to operate with a constant delivered pressure rather than with a constant back pressure so that the water pressure in the line 53 is always (for example) 35 pounds per square inch, or some other known and constant pressure. The flow of water from this line to be admixed with rosin size solution in the line 46 can therefore be controlled accurately by means of a manually operated valve 55, which is identical in its construction and operation with the valve 21 in the hot water line 20. By setting the valve 55 to give a known rate of flow, as indicated by a flow meter 56, and by adjusting this flow rate in accordance with the flow of rosin size solution in the line 46 as shown by flow meter 57, the final concentration of dilute rosin size solution can be adjusted.

The dilute and cooled rosin size solution, having the desired final concentration, is passed by line 58 into homogenizing valve 60, which is a constant back-pressure valve identical in construction and operation with the valves 3 and 34. The resulting dilute rosin size, which passes to the storage tank 61 through line 62, is both uniform in composition and constant in concentration and is suitable for any of the uses for which rosin size is ordinarily employed in a paper mill.

One of the principal advantages of the above-described system is that it can be operated automatically and without the necessity of supervision. To accomplish this the dilute rosin size storage tank 61 is provided with a float 64 that closes a switch 65 when the quantity of size falls below a predetermined level. When this switch closes it starts the gear pump 1 and also the cold water booster pump 51. Similarly, these pumps are stopped when the float-control valve 65 is opened.

When the supply of concentrated rosin size to the heater 5 is shut off, by stoppage of the gear pump 1, the problem of water evaporation and deposition of solids is encountered. In other words, there is a likelihood that the hot metal of the heater 5 will evaporate water from the residual size remaining therein when the gear pump 1 is stopped, and this would deposit solid material on the metal surfaces that would become baked to an insoluble condition and would soon plug up the passages of the heat exchanger. In order to avoid such deposition of solids a hot water line 70 controlled by a solenoid-actuated valve 71 is provided. Steam is admitted to the heating chamber of the heater through a thermostatically controlled valve 72 and a solenoid-controlled valve 73, and the electrical circuit is so arranged that the valve 73 is closed and the valve 71 is opened when the pump 1 is stopped. By this provision the steam-heating compartments of the heat exchanger 5 are immediately flooded with hot water from the line 70 when the gear pump 1 is stopped. This cools the interior of the heat exchanger, and deposition and burning of the rosin size by hot metal surfaces is prevented. It will of course be understood that the electrical interlock is such that the valve

73 is opened and the valve 71 is closed when the pump 1 is started up again so that the flow of steam to the heater 5 is resumed.

A protective system for the hot and cold water supply lines is also provided. Valve 75 in the hot water supply line 20 and valve 76 in the cold water line 53 are stop control diaphragm valves that remain open so long as there is a predetermined water pressure in the supply lines 71 and 78 respectively. These supply lines, in turn, are connected with the cold water line 80 through lines 81 and 82 by means of solenoid valves 83 and 84 which remain open as long as the switch 65 is closed and the pumps 1 and 51 are in operation. When the pump circuit is open, however, these solenoid valves are closed, which results in closing the stop control valves 75 and 76. It will be noted that these valves would also close, regardless of the electrical circuit, if the water pressure in the line 80 should fall below a predetermined value. The system of my invention is therefore protected fully against undesired dilution that might otherwise be caused by drainage from the lines during repeated starting and stopping of the supply pumps.

From the foregoing description of a preferred embodiment of my invention it will be seen that all the objects thereof are accomplished. A method is provided wherein a stream of the concentrated rosin size is heated and fed into the mixer 25 at a uniform predetermined rate, which rate can be varied by means of the speed control 2 in order to vary the concentration of the diluted rosin size. In the Venturi mixer 25 the stream of hot size is mingled with a stream of hot water delivered at a uniform predetermined rate such that the resulting size mixture has a solids content well below that of gel formation. The resulting hot, diluted size suspension is homogenized by passage through the valve 34 in order to disperse any lumps or flocks of gel, after which it is further mingled with a stream of cold water delivered at a uniform predetermined rate such as to produce a solids content of 5% or less, depending on the particular requirements of the paper mill. Provision is also made for flooding the heating surfaces of the heater 5 with hot water whenever the flow of rosin size through the passages thereof is interrupted; for maintaining a uniform supply of constant-temperature hot water from the tank 10, and of cold dilution water in the line 53. Provision is additionally made to interrupt the flow of both hot and cold water to the size dilution system when the flow of rosin size is stopped, whereby excessive dilution from residual water in the system is avoided.

What I claim is:

1. A method for the dilution of a concentrated aqueous rosin size having a concentration of about 70-80% solids which comprises establishing a stream of said size having a uniform predetermined rate, heating said stream of size to a temperature above the temperature of gel formation and within the range of 140° to 200° F., mingling said stream of size uniformly with a stream of water heated to a comparable temperature within the range of 140° to 200° F. and

delivered at a uniform predetermined rate such that the resulting size mixture has a solids content below that of gel formation and within the range of about 10-20% solids, homogenizing the resulting size, and then mingling the size with a stream of cold water delivered at a uniform predetermined rate such that the solids content of the mixture is reduced to 2-5% and again homogenizing the diluted rosin size.

2. Apparatus for diluting a concentrated rosin size solution comprising in combination a motor-driven gear pump for delivering a stream of concentrated rosin size at a predetermined constant rate, a heater containing a passage for said stream of concentrated rosin size and a steam chamber in heat exchange relation therewith, a hot water tank, means for supplying steam to said steam chamber when said gear pump is in operation, means for shutting off the steam and supplying hot water from said tank to the steam chamber when the gear pump is stopped whereby burning of residual rosin size in said heater is prevented, means for mingling and diluting the stream of hot concentrated rosin size from said heater with a stream of hot water from said tank supplied at a predetermined constant rate, a homogenizing valve and means for passing the resulting stream of diluted hot rosin size therethrough, means for adding the homogenized size solution with cold water supplied at a predetermined constant rate, and a second homogenizing valve and means for passing the diluted and cooled rosin size dispersion therethrough.
3. Apparatus for diluting a concentrated rosin size solution comprising in combination a motor-driven gear pump for delivering a stream of concentrated rosin size at a predetermined constant rate, a heater containing a passage for said stream of concentrated rosin size and a steam chamber in heat exchange relation therewith, a hot water tank having an external hot water recirculation system containing a circulating pump, a steam injector and a back pressure valve, a Venturi mixer having a rosin size inlet connected to the rosin size outlet of said heat exchanger and a water inlet connected by a pipe containing a hot water stop control valve to a point in said hot water recirculation system between the circulating pump and the back pressure valve, a homogenizing valve and means for passing hot diluted rosin size from said Venturi mixer therethrough, a second homogenizing valve having an outlet pipe leading to a dilute rosin size storage tank, a dilution pipe connecting the two homogenizing valves, a cold water pipe provided with a cold water stop control valve joining said dilution pipe to a source of cold dilution water at constant pressure, and means for shutting off the steam and substituting hot water in the steam chamber of said heat exchanger and for simultaneously closing said hot and cold water stop control valves when the motor-driven gear pump is stopped.
